OR D11,606

EX

D11,606

UNITED STATES PATENT OFFICE.

RODOLPHE CHRISTESEN, OF HARTFORD, ASSIGNOR TO THE RUSSELL & ERWIN MANUFACTURING COMPANY, OF NEW BRITAIN, CONNECTICUT.

DESIGN FOR HINGES.

SPECIFICATION forming part of Design No. 11,606, dated January 13, 1880.

Application filed June 18, 1879. Term of patent 14 years.

To all whom it may concern:

Be it known that I, RODOLPHE CHRISTESEN, of the city and county of Hartford, and State of Connecticut, have invented a new and useful 5 Design for Door-Hinges; and I do hereby declare that the following specification, taken in connection with the accompanying photographic illustration, forming a part of the same, is a full, clear, and exact description 10 thereof.

Heretofore door-hinges have been variously ornamented; but, so far as my knowledge extends, the wings thereof have always been ornamented in counterpart, and the knuckles 15 thereof, whether plain or ornamented, have always had the effect of dividing elements by which the ornamented wings were separated from each other.

The prime object sought by me is to so ornament the knuckle that it shall not have this dividing or separating effect, as heretofore, but serve rather to blend with and cause the designs on the two wings of the hinge to harmonize, regardless of their specific differences.

The design hereinafter described is adapted 20 to the wings and knuckle of a door-hinge, and it possesses, in addition to the specific ornamentation, the novel characteristic that the design upon one wing differs in detail from that 25 upon the other wing, yet the ornamentation of the respective wings and that of the knuckle form component parts of one whole pictorial design.

The specific ornamentation chosen to illustrate this novel feature in designs for butts 30 is in the Japanese style, and is composed as follows:

Referring to the accompanying illustration, A denotes the knuckle, and B B' the wings, of 35 the butt. The lower portion of the knuckle A is ornamented by a transverse band, a, in imitation of marquetry, which is surmounted by a vase, a', holding a flowering shrub, the 40 stems and leaves of which extend over upon

the wings B B'. The upper portion of the 45 knuckle is ornamented by a plain raised band, a², and a portion of a section of fish-scale or tile ornament, a³, which also occupies the upper right and left hand corner of the wings B 50 B', respectively.

Each of the wings B B' is surrounded by a plain raised band, b, and the general surface or ground is mottled to give effect to the design. The central portion of the wing B is occupied by a male figure, b', represented as 55 standing upon one-half of an inclined bridge, b², and facing a female figure, b³, upon the central portion of the wing B'. This latter figure bears an umbrella, and is represented as descending the other half of the bridge b² and 60 approaching the figure b'. A geometrical border, b⁴, ornaments the outer side of the wing B, and occupying its upper left hand corner is a portion of a flowering shrub, b⁵, from which depends a lantern, b⁶. The outer side of the 65 wing B' is ornamented by flowering shrubs b⁷.

It is to be understood that the design above described is chosen to illustrate the novel feature in designs for door-hinges, which feature consists in ornamenting the respective wings 70 and the knuckle with different designs which form component parts of the whole design upon the surface of the butt. Therefore,

What I claim, and desire to secure by Letters Patent, is—

1. The knuckle-joint ornamentation for 75 hinges, substantially as shown and described, overlapping one or both wings.

2. The design for hinges, substantially as 80 shown and described, embodying distinct designs on each wing of the hinge, and the knuckle-joint ornamentation overlapping the wings, each constituting a component part of one whole design.

RODOLPHE CHRISTESEN.
